CLAIM

I claim the ornamental design for the planter, as shown and described.

DESCRIPTION

FIG. 1 is an upper perspective view of a planter showing my design;

FIG. 2 is a lower view thereof;

FIG. 3 is a top view thereof;

FIG. 4 is a bottom view thereof;

FIG. 5 is a right side view thereof;

FIG. 6 is a left side view thereof;

FIG. 7 is a rear view thereof; and,

FIG. 8 is a front view thereof.
